[73] Assignee: **Murlyn Enterprises Ltd.**, Orillia, Canada

[**] Term: **14 Years**

[21] Appl. No.: **35,273**

The ornamental design for an emergency signalling sleeve to be worn on the arm, as shown and described.

[22] Filed: **Feb. 23, 1995**

DESCRIPTION

[30] Foreign Application Priority Data

Feb. 15, 1995 [CA] Canada 1995-0378

FIG. 1 is an elevation view in a flattened condition of an emergency signalling sleeve to be worn on the arm of this invention, the opposing side being a mirror image of that shown;

[52] U.S. Cl. **D10/109; D2/610**

FIG. 2 is a perspective view thereof illustrating the manner of use of the design, with the broken line showing for illustrative purposes only and forming no part of the claimed design;

[58] Field of Search ..... D2/610, 612; D10/109, D10/111, 121, 114; D29/100, 120, 121; 359/516, 517, 519; 2/170; 116/63 R

FIG. 3 is a further perspective view thereof; and, FIG. 4 is a reduced elevation view thereof showing the manner of use of the design.
